UNITED STATES PATENT OFFICE

107,753

DESIGN FOR A GLOVE MEASURING DEVICE

Robert M. Eisendrath, Chicago, Ill., assignor to
The Eisendrath Glove Company, Chicago, Ill.,
a corporation of Illinois

Application November 10, 1937, Serial No. 72,764

Term of patent 14 years

To all whom it may concern:

Be it known that I, Robert M. Eisendrath, a citizen of the United States, residing at Chicago, in the county of Cook and the State of Illinois, have invented a new, original, and ornamental Design for a Glove Measuring Device, of which the following is a specification, reference being had to the accompanying drawing, forming a part thereof.

Figure 1 is a front elevation of a glove measuring device showing my new design;

Figure 2 is a top plan view thereof;
Figure 3 is a side elevation;
Figure 4 is a rear elevation; and
Figure 5 is a side elevation from the opposite side of Figure 3.

I claim:

The ornamental design for a glove measuring device, as shown.

ROBERT M. EISENDRATH.
